UNITED STATES PATENT OFFICE.

ALDEN E. OSBORN, OF NEW YORK, N. Y.

AUTOMATIC TRAIN-CONTROLLING MECHANISM.

SPECIFICATION forming part of Letters Patent No. 738,349, dated September 8, 1903.

Application filed May 8, 1902. Serial No. 106,397. (No model.)

To all whom it may concern:

Be it known that I, ALDEN E. OSBORN, a citizen of the United States, and a resident of the city of New York, borough of the Bronx, in 5 the county and State of New York, have invented a new and Improved Automatic Train-Controlling Mechanism, of which the following is a full, clear, and exact description.

The purpose of this invention is to provide 10 improved means for automatically stopping a car or train of cars independently of the persons in charge and of the signal apparatus of the railway should such apparatus be employed.

15 By means of my invention the source of power is cut off, brakes are applied, and this is done automatically by utilizing the fluid-pressure of the brake system or of the motive power for driving the train or any other source 20 of fluid-pressure, whereby to furnish the energy necessary for throwing the valve or other devices required to be operated in order to bring about the desired end. In the case of a steam-locomotive this fluid-pressure 25 may be brought from the steam-boiler. If the car or train is equipped with fluid-pressure brakes, the air-pressure from the main reservoir may be utilized, or connections may be made from any other source of power available, so that upon the operation of the trip 30 devices employed this power will be thrown into action and the movement of the train arrested.

This specification is an exact description of 35 several forms of the invention, while the claims define the actual scope thereof.

Reference is to be had to the accompanying drawings, forming a part of this specification, in which similar characters of reference indicate corresponding parts in all the views.

Figure 1 is a view showing diagrammatically the application of a fluid-pressure operating device to the throttle-lever of a locomotive, this view illustrating the general 45 class of inventions to which mine belongs. Fig. 2 illustrates one form of my invention whereby the power and brake systems are connected to be worked in a certain herein-after-described relation. Fig. 3 shows the invention applied independently to the engineer's valve of the brake system. Fig. 4 is a

view illustrating a modified form of the invention which provides for two separate movements of the engineer's valve of the brake system, thus to secure a service or an 55 emergency operation of the brakes, as may be desired; and Figs. 5 and 6 are views showing different manners of attaining the end referred to in connection with Fig. 1.

Referring to Fig. 1, *a* indicates the throttle-lever, as the device is shown as used in a steam-locomotive. *b* indicates a fluid-cylinder provided at its broad or outer end with an exhaust-port *c* and at its near or inner end with a vent *d*. In this cylinder works a piston *e*, connected by a rod *f* or in any suitable manner with the throttle-lever *a*. *g* indicates a pipe extending from a source of fluid-pressure, as above explained, and *h* indicates a valve, which may be of any form desired, 60 this valve being interposed between the supply-pipe *g* and a pipe *i*, leading to the near or inner end of the cylinder *b*. The valve *h* is operated by a swinging arm *k*, connected with its stem, and *l* indicates a dog adapted 65 to coact with a ratchet *m* on the arm *k*, whereby to hold the arm in active position after said arm has been moved thereto, although any other equivalent arrangement may be used. These parts above described are carried on the locomotive or other part of the 70 train of cars, and *n* indicates a cam-plate, which is mounted along the track and which is hinged or otherwise arranged so as to be 75 thrown in and out of the path of the arm *k*. 80

In the practical use of the invention the cam-plate *n* is connected with the signaling apparatus, to be operated either manually or automatically, and the parts are so arranged that when a train is to be arrested the 85 plate *n* is thrown up into the path of the arm *k*. As the train passes the arm *k* is caused to ride over the cam-plate and the valve *h* is opened. The fluid-pressure then passes through the pipe *i* into the end of the cylinder *b*, 90 and the piston *e* is caused to move to the left, carrying with it the throttle-lever and shutting off the steam-supply to the engine of the locomotive. After the piston *e* passes the 95 exhaust-port *c* the fluid-pressure is exhausted into the atmosphere. The vent *d* is provided in order to permit the easy manual operation 100

of the lever a by preventing compression in the near or inner end of the piston. This vent is not, however, of sufficient area materially to interfere with the action of the fluid-pressure as it enters the cylinder b from the pipe i . The same end may be attained by fitting the piston so loosely in the cylinder as to allow a certain quantity of pressure to leak past the piston.

10 In the construction shown in Fig. 2 the piston e works in a cylinder b' , to the inner end of which the pipe i leads, as before explained. This cylinder has a vent d' , the same as the vent d ; but its exhaust-port c' is joined to a pipe o , which leads to a cylinder p , in which works a piston q , connected with the engineer's valve r of the brake system. The cylinder p has a vent s for the same purpose as the vents d and d' , and the opposite end of the cylinder is open to the atmosphere, as shown. In this form of the invention as the fluid-pressure passes through the pipe i and actuates the piston e , as before described, it moves the piston past the exhaust-port c' , and the fluid-pressure after having done its duty in the cylinder b' passes by the pipe o to the cylinder p and throws the engineer's valve r . By this mechanism the throttle of the locomotive is first operated 25 to shut off the motive power and then the engineer's valve is thrown to apply the brakes. In Fig. 2 it is supposed that the pipe i is connected with a valve and valve-operating devices the same as or equivalent 30 to those shown in Fig. 1.

35 If desired, the power-controlling and the brake-applying devices may be connected with independently-operating cylinders performing the same functions as the cylinders b' and p in Fig. 2. In this case the arrangement may be, for example, the same as that shown in Fig. 1, with the arrangement shown in Fig. 3 added thereto, although if it is only desired to automatically operate the brakes 40 this arrangement may be used alone.

45 p^2 in Fig. 3 indicates the cylinder in which works the piston q^2 , connected with the engineer's valve r . The cylinder p^2 has a vent s' , the same as the vent s in Fig. 2, and an exhaust-port s^2 . h^2 indicates a valve for providing for the passage of the fluid-pressure through a pipe o^2 , and this valve is operated by a swinging arm k^2 . h^3 indicates the stem of the valve h^2 , and l' indicates a cam fastened 50 to the axis of the arm k^2 , so as to swing therewith. This cam l' serves to operate the valve-stem h^3 and also to lock the arm k^2 in operative position after it has been thrown by a cam-plate or other operating device equivalent to the element n in Fig. 1. As the arm k^2 swings in the direction of the arrow in Fig. 3 the cam l' rides past the stem h^3 and throws the stem so as to open the valve, after which the cam engages its radial side with the valve-stem, and thus the return of the arm k^2 is prevented. As the piston q^2 is moved the valve

70 r is operated, and this movement of the piston continues until the piston passes the exhaust-port s^2 , after which the fluid-pressure is exhausted into the atmosphere.

75 Under certain conditions of railway service it may be necessary or advisable to operate the engineer's valve twice, once to produce a service or partial application of the brakes and the second time to produce an emergency or complete application of the brakes. In Fig. 4 I have shown a mechanism for first cutting off the motive power and effecting a service or partial application of the brakes, and then should the train or car 80 run on into immediate danger an emergency or complete application of the brakes is effected. In this view, a' indicates the lever or handle for controlling the motive power, and r indicates the engineer's valve of the brake system. b^2 indicates a cylinder in which works a piston e' , connected by a rod f' with the lever a' . The cylinder b^2 has a vent d^2 , the same as the vents d and d' , before described, and the exhaust-port c^2 of the cylinder b^2 communicates by a pipe o' with a cylinder p' . In this cylinder works a piston q' , connected by its rod with the engineer's valve r . In the cylinder p' are formed two ports t and t' , located at different positions along the length thereof and operating as will be hereinafter described. The pipe o' leads into the cylinder b^2 , and h' indicates a valve similar to the valve h , before described. This valve is 90 operated by a swinging arm k' , adapted to be actuated by a cam-plate n' , as before described. g' indicates the pipe for leading the fluid-pressure to the valve h' . u indicates a second valve communicating by a pipe u' with the pipe o' and having the fluid-pressure led thereto by a pipe u^2 similar to the pipes g and g' , before described. v indicates a swinging arm for operating the valve u , this arm being similar to the arms k and k' , before described, and being adapted to be actuated by a cam-plate n^2 similar to the cam-plates n and n' .

95 In the practical operation of the device, as shown in Fig. 4, the cam-plates n' and n^2 are placed at different positions along the track, the relative location being of course determined by the peculiar conditions to be dealt with. Assuming that the danger is ahead and the signals have been properly operated, the cam-plate n' , which is located in advance 100 of the plate n^2 , will be thrown down, thus operating the arm k' and opening the valve h' . The fluid-pressure now passes into the cylinder b^2 and operates the lever a' , moving it into the closed position, which is shown in the 105 view referred to. After the piston e' reaches the position shown, the fluid-pressure passes by the port c^2 through the pipe o' into the cylinder p' . The port t of this cylinder is so proportioned that after the piston q' passes 110 this port said port will be capable of exhausting the entire working pressure remaining in

the pipe o' , and therefore the movement of the piston q' will cease and the valve r will be but partly thrown. These elements may be adjusted so that this partial application 5 of the engineer's valve will constitute the service application of the brake, or, indeed, any other operation that it might be desired to perform upon the engineer's valve. By the operations above described the motive power 10 is cut off and the brakes are partly applied. Should the train not come to a standstill, but should it run on into immediate danger, the signaling apparatus having been so constructed or arranged as to throw down the cam-plate 15 n^2 simultaneously with the distant plate n' , its continued movement would bring the swinging arm v into engagement with this cam-plate, throwing the arm and opening the valve u . This valve permits a second volume 20 of the fluid under pressure to pass into the pipe o' and from thence to the cylinder p' . The parts are so proportioned that this second volume of fluid is so great that it cannot be all exhausted through the port t of the 25 cylinder p' , and therefore the piston q' is moved farther and the valve r is thrown farther, this movement continuing until the piston q' passes the port t' , after which both ports t and t' are then opened to the atmosphere, 30 and the fluid-pressure is then completely exhausted. By this action a complete or emergency application of the brakes is effected.

As to the means for operating the cam-plates 35 or the other devices which may be employed to throw the arms h , h' , and v these may be of any sort desired and form no part of the present invention. They may be connected with the automatic signal apparatus, so as to 40 be thrown automatically, or, if desired, they may be connected with manually-operated devices, or both. In Fig. 4 I have illustrated cams l^2 connected with the arms h' and v to hold said arms after they have been thrown, 45 these cams l^2 being the same as the cam l' , before described. Any other means suitable for this purpose may of course be employed.

In order to avoid that delicacy of adjustment of pressures and movements involved 50 in the construction shown in Fig. 4, I have devised the devices shown in Figs. 5 and 6, in which the pipes o' and u' are led separately to the cylinder for operating the engineer's valve or other part of the brake system.

Both of these pipes o' and u' are controlled 55 by valves the same as shown in Fig. 4; but in Figs. 5 and 6 these pipes o' and u' have no immediate connection with each other. Referring to Fig. 5, the cylinder therein is divided into two parts p^3 and p^4 , separated from each other by a web p^5 . In the part p^3 works a piston q^3 , and in the part p^4 works a piston q^4 . These pistons are connected by a rod q^6 , which passes loosely through the web p^5 , and the piston q^3 is connected by a rod q^6 60 with the engineer's valve. The pipe o' leads into the inner end of the division p^3 of the

cylinder, and this division is formed with an exhaust-port p^6 intermediate the length of the stroke of the piston q^3 . The pipe u' leads 70 into the inner end of the part p^4 of the piston, and this pipe is formed with an exhaust-port p^7 at the limit of the outstroke of the piston q^4 . When, therefore, the pressure passes through the pipe o' from the cylinder which 75 operates the power-controller, this pressure is exerted against the piston q^3 and the piston is moved until it passes the port p^6 , whereupon the pressure is exhausted into the atmosphere and the engineer's valve r is but 80 partly thrown. Should the second or emergency application be necessary, the fluid-pressure will be introduced into the pipe u' in the manner before explained and then this pressure will be exerted against the piston 85 q^4 , moving this piston on until the full length of its throw has been completed, whereupon said piston passes the port p^7 and the fluid-pressure of the pipe u' is exhausted. This effects a complete or emergency application 90 of the brake. It should be of course understood that the pistons q^3 and q^4 move as a unit.

In Fig. 6, p^8 indicates the cylinder, in which works a piston q^7 , connected by its rod q^8 95 with the engineer's valve r . In the inner end of this cylinder p^8 is formed a passage p^9 , with the intermediate part of which the pipe o' communicates, the outer end of said passage being open to the atmosphere. In this 100 passage p^9 plays a small plug-like valve q^9 , connected with the piston q^7 by means of a rod q^{10} . The pipe u' enters into the inner end of the cylinder p^8 , and the outer portion of this cylinder is formed with an exhaust-port p^{10} . When the pressure passes first from the pipe o' , it enters the passage p^9 and through this passage into the cylinder operating the piston q^7 . This piston carries with it the valve q^9 , and the operation of the parts continues until this valve passes the mouth of the pipe o' . Then this pipe is placed in direct communication with the atmosphere and the fluid-pressure in said pipe is exhausted. This will have served partly to throw the 115 valve r . Then if the pressure is applied to the pipe u' it passes directly into the cylinder p^8 and continues the movement of the piston q^7 until the exhaust-port p^{10} is passed, whereupon the pressure of the pipe u' is also 120 exhausted and the valve r is fully thrown.

Various changes in the form and details of my invention may be resorted to at will without departing from the spirit of my invention. Hence I consider myself entitled to 125 all forms of the invention as may lie within the intent of my claims.

Having thus described my invention, I claim as new and desire to secure by Letters Patent—

1. In a motor-driven vehicle, the combination with the means for controlling the motive power and with the brake system thereof, of fluid-pressure-actuated devices for op-

erating said mechanism in succession, and means for automatically throwing said fluid-pressure-actuated devices into action, said means for throwing the fluid-pressure-actuated devices into operation being mounted stationary independently of the vehicle.

2. In a motor-driven vehicle, the combination with the means for controlling the motive power and with the brake system, of fluid-pressure cylinders, pistons therein respectively in connection with said power-controlling means and the brake-controlling system, means for leading the fluid-pressure into and through the cylinder of the power-controlling means to the cylinder of the brake-controlling system, and an additional means for leading a second volume of fluid under pressure to the second-named cylinder.

3. In an automatic train-controlling mechanism, the combination of a fluid-pressure cylinder having two inlets thereto and having an exhaust-port opposite said inlets, a piston working in the cylinder, and a valve in connection with the piston and commanding one of the inlets to the cylinder, for the purpose specified.

4. In a motor-driven vehicle, the combination with the means for controlling the motive power and the brake system of the vehicle, of two fluid-actuated devices respectively for operating said power and brake controlling means, and separate devices for automatically controlling the fluid-actuated devices.

5. In a motor-driven vehicle, the combination with the means for controlling the motive power and the brake system of the vehicle, of two fluid-actuated devices respectively for actuating said power and brake controlling means, and means for automatically supplying the fluid in succession to said fluid-actuated devices to cause them to operate the one following the other.

6. In an automatic-controlling means for vehicles, the combination of two fluid-pressure-operated devices adapted to work in succession, means for supplying the fluid-pressure to the first of said devices, and a pressure-communicating means extending from the exhaust of the first device to the second device to operate the latter.

7. In a motor-driven vehicle the combination with the power and brake controlling means, of a fluid-pressure-operated device in operative connection with each of said means, means for supplying fluid-pressure to the first of said fluid-pressure-operated devices, and a pressure-communicating means extending from the exhaust of the first fluid-pressure-operated device to the second fluid-pressure-operated device to operate the latter, whereby the power-controlling means is operated first and the brake-controlling means second.

8. In an automatic controlling means for vehicles, the combination of two fluid-pressure-operated devices adapted to work in succession, means for supplying the fluid-

pressure to the first of said devices, a pressure-communicating means extending from the exhaust of the first device to the second device to operate the latter, and a second means for supplying fluid-pressure leading directly to the second fluid-pressure-operated device.

9. In a motor-driven vehicle the combination with the power and brake controlling means, of a fluid-pressure-operated device in operative connection with each of said means, means for supplying fluid-pressure to the first of said fluid-pressure-operated devices, a pressure-communicating means extending from the exhaust of the first fluid-pressure-operated device to operate the latter, whereby the power-controlling means is operated first and the brake-controlling means second, and a second means for supplying fluid-pressure leading directly to the second fluid-pressure-operated device, further to operate the second fluid-pressure-operated device.

10. In an automatic controlling means for vehicles, the combination of two fluid-pressure-operated devices adapted to work in succession, means for supplying the fluid-pressure to the first of said devices, a pressure-communicating means extending from the exhaust of the first device to the second device to operate the latter, a second means for supplying fluid-pressure leading directly to the second fluid-operated device, and two independent operating members stationary at different points in the path of the vehicle respectively for the two means for supplying fluid-pressure whereby to permit operating the pressure-supplying means separately and at different points.

11. In a motor-driven vehicle the combination with the power and brake controlling means, of a fluid-pressure-operated device in operative connection with each of said means, means for supplying fluid-pressure to the first of said fluid-pressure-operated devices, a pressure-communicating means extending from the exhaust of the first fluid-pressure-operated device to the second fluid-pressure-operated device to operate the latter, whereby the power-controlling means is operated first and the brake-controlling means second, a second means for supplying fluid-pressure leading directly to the second fluid-pressure-operated device, further to operate the second fluid-pressure-operated device, and two independent operating members stationary at different points in the path of the vehicle respectively for the two means for supplying fluid-pressure whereby to permit operating the pressure-supplying means separately and at different points.

12. In an automatic controlling means for vehicles the combination of two fluid-pressure-operated devices in operative connection with different parts of the vehicle and adapted to work in succession, two means respectively for supplying fluid to said devices, and two independent operating members stationary

at different points in the path of the vehicle and respectively for the fluid-supply means whereby to permit operating said means separately and at different points.

5 13. In an automatic controlling means for vehicles the combination of two fluid-pressure-operated devices in operative connection with different parts of the vehicle and adapted to work in succession, two means respectively 10 for supplying fluid to said devices, and two independent operating members stationary at different points in the path of the vehicle and respectively for the fluid-supply means whereby to permit operating said means separately and at different points, said operating members consisting of cams mounted to swing in and out of active position.

14. The combination of a fluid-pressure cylinder having two inlets therein, one of 20 said inlets opening into a passage in the cylinder and said passage being disposed longitudinally of the bore of the cylinder, a piston working in the cylinder, a stem attached to the piston, and a plug-valve attached to the 25 stem and working in the said passage, the plug-valve being movable to cover the cylinder-inlet of the passage.

15. In a motor-driven vehicle the combination with the means controlling the power 30 and brake system, of separate devices respectively for independently operating said controlling means, and operating members respectively for said separate devices, the operating members being stationary at different 35 points in the path of the vehicle for the purpose specified.

16. In a motor-driven vehicle the combination with the power and brake controlling means, of separate devices respectively for 40 operating said power and brake controlling means, means for actuating the said devices of the power-controller, a connection extending from the operating device of the power-controller to the operating device of the brake-controller to apply the brake upon the action 45 of the operating device of the power-controller, and a separate means for separately and further actuating the operating device of the brake-controller.

50 17. In a motor-driven vehicle the combination with the controlling means of the power and brake system, of a cylinder and piston in

connection with the power-controller, a cylinder and piston in connection with the brake-controller, a pressure-communicating means 55 extending from the exhaust of the first cylinder to the feed of the second, and separate means for supplying fluid-pressure to the respective cylinders.

18. In a motor-driven vehicle the combination with the controlling means of the power and brake system, of a cylinder and piston in connection with the power-controller, a cylinder and piston in connection with the brake-controller, a pressure-communicating means 60 65 extending from the exhaust of the first cylinder to the feed of the second, a separate means for supplying fluid-pressure to each cylinder, and two independent operating members for said separate means, the operating members 70 being stationary at different points in the path of the vehicle for the purpose set forth.

19. In a controlling means for fluid-pressure brake systems, the combination with the 75 brake-valve, of means for automatically imparting two separate and successive movements thereto, whereby to effect a service or an emergency application of the brakes.

20. In a controlling means for fluid-pressure brake systems, the combination with the 80 brake-valve, of means for automatically imparting two separate and successive movements thereto, whereby to effect a service or an emergency application of the brakes, and two separate operating members for said 85 means placed at different points along the path of the vehicle to which the brake system is applied.

21. In a controlling means for power-driven vehicles, the combination with the controlling 90 element of the vehicle, of means for automatically imparting two separate movements to said controlling means, and operating devices for said means, the operating devices including two members placed at different points 95 along the path of the vehicle, for the purpose specified.

In testimony whereof I have signed my name to this specification in the presence of two subscribing witnesses.

ALDEN E. OSBORN.
